ALEXANDER R. GOLDEN, OF NEW YORK, AND JULIUS I. KAHN, OF BROOKLYN,
NEW YORK

MERCHANTISING FABRIC

Application filed May 17, 1927. Serial No. 191,986.

Our invention relates to improvements in the merchandising of fabrics such as shirts, shirt waists, and the like, and more particularly has reference to a stiffening card 5 adapted to be inserted in the folds of the garment and to fasten about the same after the same has been folded, to retain the garment in compact, neat, and flat form for shipment and handling.

10 Heretofore, it has been customary to use a rectangular flat piece of card, about one-sixteenth of an inch thick, which in shirts is folded within the same, the arms being secured by pins, and likewise the bottom of 15 the shirt, after which a paper band is pinned around the same to hold the folds in position. The pins are an annoyance and sometimes remain in the shirt, causing irritation when the shirt is applied, and the paper band frequently becomes broken, loosening the folds 20 of the garment, whereas according to the preferred embodiment of our invention, substantially the same piece of card is employed, preferably strengthened with a fabric covering, and is cut out in such a manner as to 25 provide fastening means and a flap, so that in folding the garment, the same is securely retained therein without the necessity of pins, paper bands, or other means.

30 In the accompanying drawings, we have illustrated in Fig. 1, in front elevation, a suitable embodiment of our invention as applied to a gentleman's negligee shirt. Fig. 2 is a back view of the same. Fig. 3 is a 35 plan view of the card, showing the partly cut-out portions. Fig. 4 is another view of said card in perspective, with the partly cut-out portions opened out, and Fig. 5 is a perspective view of the card before any of the 40 portions have been cut out.

The usual rectangular card insert 6 is 45 preferably covered with a piece of fabric, such as linen 7, after which the center of the same is cut out by die or other suitable means along the lines indicated by the reference characters 8, 9, and 10, likewise the straps 11 and 12 are cut out, the panel 13 remaining hinged at 14, and the straps being hinged at 15, 16, the lower end of one strap having an 50 enlargement 17 with slits 18, 19, through

which the end 20 of the other strap passes, as shown in Fig. 1. In applying the insert, the shirt is laid face down with the frame of the insert thereon, and the sides are folded over with the arms folded in and parallel in the usual manner, the panel 13 remaining up clear of the frame 21, over which the sides of the shirt are folded. After this, the tail or bottom of the shirt, which has already been folded in, is thrown up, and 60 down over the sides in the usual manner, and then the panel 13 is laid over with the straps 11, 12, extending outwardly. These straps are then folded around over the front of the shirt, as shown in Fig. 1, the ends of the strap 11 passing through the loop formed by the slits 18, 19, as shown, thus completely and neatly holding the folded garment with its reinforcing insert substantially as shown. Garments thus secured can be 70 handled with greater freedom, and less likelihood of becoming unfolded, and provide a much better way of merchandising the goods without appreciably adding to the cost. The fabric covering upon the insert provides greater rigidity and strength, at the same time insuring good hinge connection between the panel 13 and frame 21, and the straps 11, 12, and the panel 13, as well as improving the appearance of the article 80 on display.

Of course it will be understood that various modifications may be made in the construction and arrangement of parts without departing from the spirit of the invention 85 as claimed.

We claim:

1. An insert of the class described comprising a substantially rectangular card having a substantially rectangular central portion cut out of the same and hinged at one end, and hinged cut outs in said central portion adapted to be secured transversely around said insert.

2. A shirt insert of the class described comprising a substantially rectangular body portion, a hinged central section therein and means in combination therewith for securing the shirt thereupon by straps extending 100

from said central section transversely across
said shirt.

In testimony whereof we hereunto affix
our signatures.

5
